L.L.P.(57) CLAIM

The ornamental design for a shoe outsole, as shown and described.

DESCRIPTION

FIG. 1 is a rear perspective view of a shoe showing my design;

FIG. 2 is a first-side, front perspective view thereof; and,
FIG. 3 is a second-side, front perspective view thereof.

The long-and-short broken lines form an unclaimed boundary around the claimed subject matter, and form no part of the claim. The even-length broken lines, which show the remainder of the article, are directed to environment, represent unclaimed subject matter, and form no part of the claimed design.

1 Claim, 3 Drawing SheetsFIG. 2.
